(57) **CLAIM**

The ornamental design for a hat shaping device, as shown and described.

DESCRIPTION

FIG. 1 is a perspective view of a first embodiment of my new design for a hat shaping device, including a first component and a second component, shown in a first example configuration;

FIG. 2 is side view thereof, shown in a second example configuration;

FIG. 3 is another side view thereof, shown in a third example configuration;

FIG. 4 is a perspective view of the first component, shown separately for clarity of illustration;

FIG. 5 is a left side view thereof, the right side view being the mirror image thereof;

FIG. 6 is a front view thereof;

FIG. 7 is a rear view thereof;

FIG. 8 is a top view thereof;

FIG. 9 is a bottom view thereof;

FIG. 10 is a perspective view of the second component, shown separately for clarity of illustration;

FIG. 11 is a left side view thereof, the right side view being the mirror image thereof;

FIG. 12 is a front view thereof;

FIG. 13 is a rear view thereof;

FIG. 14 is a top view thereof;

FIG. 15 is a bottom view thereof;

FIG. 16 is another perspective view of the hat shaping device, showing an example illustration of use;

FIG. 17 is a perspective view of a second embodiment of my new design for a hat shaping device, including a first component and a second component, shown in an example configuration;

FIG. 18 is a perspective view of the first component, shown separately for clarity of illustration;

(Continued)

FIG. 19 is a left side view thereof, the right side view being (56)
 the mirror image thereof;
 FIG. 20 is a front view thereof;
 FIG. 21 is a rear view thereof;
 FIG. 22 is a top view thereof;
 FIG. 23 is a bottom view thereof;
 FIG. 24 is a perspective view of the second component, shown separately for clarity of illustration;
 FIG. 25 is a left side view thereof, the right side view being the mirror image thereof;
 FIG. 26 is a front view thereof;
 FIG. 27 is a rear view thereof;
 FIG. 28 is a top view thereof; and,
 FIG. 29 is a bottom view thereof.

The dot-dash-dot broken lines in the drawings represent an unclaimed boundary line and form no part of the claimed design.

The dash-dash broken lines in FIG. 16 depict environmental subject matter and form no part of the claimed design. The remaining dash-dash broken lines illustrate portions of the article that form no part of the claimed design.

1 Claim, 17 Drawing Sheets
